UNITED STATES PATENT OFFICE

2,462,945

VARIABLE PREDETERMINED NUMBER
PULSE GENERATORRobert W. Carlson, Depew, N. Y., assignor to
Colonial Radio Corporation, Buffalo, N. Y.

Application August 14, 1944, Serial No. 549,317

4 Claims. (Cl. 177—380)

1

This invention relates to a pulse-keying circuit; that is to say, a circuit which will deliver pulses suitable for controlling one or more transmitters to cause the same to transmit energy in relatively short pulses of any one of a predetermined number; such as, 2, 3, 4, 5, or more, corresponding to the closure of a particular switch in the control circuit.

In the arrangement herein disclosed the apparatus is constructed and arranged to deliver pulse groups consisting of 2, 3, 4, 5, and 7 pulses respectively, these pulses being of the order of a few microseconds' duration, and the spacing between successive pulses being always 1 millisecond. It will be understood, however, that in accordance with the principles of my invention, the duration of the pulses may be different and the time interval between successive pulses may also be different.

When used with receivers which respond selectively to the number of incoming pulses, a very effective remote control system may be provided for operating various mechanisms.

It is an object of this invention to provide apparatus of the class described, by means of which any one of a number of predetermined pulse combinations may be produced, the varying pulse combinations being made up of a different number of pulses of the same length always occurring at the same rate or with the same time interval between successive pulses.

It is a further object of this invention to provide apparatus of the class described capable of delivering pulses of a few microseconds' duration with a spacing between successive pulses of the order of 1 millisecond.

It is still a further object of this invention to provide apparatus of the class described, in which the time duration of the pulses and the time interval between the pulses may be readily adjusted or controlled.

It is still a further object of this invention to provide apparatus of the class described which shall be positive, reliable, and unfailing in operation.

Still other objects and advantages of my invention will be apparent from the specification.

The features of novelty which I believe to be characteristic of my invention are set forth with particularity in the appended claims. My invention itself, however, both as to its fundamental principles and as to its particular embodiments, will best be understood by reference to the specification and drawing, in which

Fig. 1 is a circuit diagram of one form of cir-

2

cuit according to my invention and Figs. 2a to 2e, 3a to 3e, 4a to 4e, 5a to 5e, 6a to 6e, and 7a to 7e are curves illustrating the operation of my invention.

5 Referring now more particularly to Fig. 1, the pulse keyer according to the embodiment of my invention disclosed herein is arranged so as to be capable of producing five different and distinctive signals, and for this purpose switches S1, S2, S3, and S4 are provided, connected so that any one of four different distinctive signals may be produced by closure of any one of the switches S1 to S4.

10 Each one of the switches is provided with a front contact, normally open, against which the blade of the switch may be closed, and each is provided with a back contact which is normally closed (biased to back contact) but is opened when the switch is moved to close on front contact.

15 Back contact S1b of switch S1 is connected to the blade of switch S2, back contact S2b of switch S2 is connected to the blade of switch S3, and back contact S3b of switch S3 is connected to blade of switch S4, so that it will be seen that when no switch is closed a circuit is completed through the back contacts of all the switches in series. This corresponds to the fifth condition, and when this condition exists, a clearing signal 20 is sent.

25 It will be seen further that upon closure of any one of switches S1 to S4 against its front contact S1f, S2f, S3f, or S4f, the series circuit through all of the switches will be interrupted and the control circuit will be established 30 through the switch which is closed. Conversely, when this switch is released, it closes on its back contact and re-establishes the clearing control circuit.

35 Control is established through resistances R1, R2, R3, and R4 connected in series from the +B source to ground when the respective switch is closed. The common point of resistances R1 and R2 may be connected to front contact S4f of switch S4, the common point of resistances 40 2 and 3 to front contact S3f of switch S3, the common point of resistances 3 and 4 to front contact S2f of switch S2, and the other point of resistance 4 to front contact S1f of switch S1.

45 The blades of switches S1 to S4 inclusive may be connected to ground when in back contact position.

50 The common point of resistances R3 and R4 may be connected to ground through condenser 55 C4, the common point of resistances R2 and R3

to ground through condenser C_5 , and the common point of resistances R_1 and R_2 to ground through condenser C_6 ; and a condenser C_3 may be connected from ground to front contact S_1 of switch S_1 .

Condenser C_1 and resistance R_5 may be connected in series across condenser C_3 , and the voltage developed across resistance R_5 may be impressed on the input circuit of tube T_1 . This tube may be a tube of the thyratron type having cathode T_{1c} , control electrode T_{1g} , shield grid T_{1sg} , and anode T_{1a} .

The common point of resistance R_5 and condenser C_1 may be connected to the control electrode T_{1g} of tube T_1 , and the common point of resistance R_5 and condenser C_3 to cathode T_{1c} . Anode T_{1a} may be connected through resistance R_8 to the source of B voltage, and screen grid T_{1sg} may be connected through resistance R_6 to cathode T_{1c} and through condenser C_2 and resistance R_7 to the $+B$ supply.

The common point of condenser C_2 and resistance R_7 may be connected to ground through condenser C_7 and also to back contact S_4b of switch S_4 . Blade of switch S_1 may be connected to ground. The output of anode T_{1a} may be impressed upon tube T_2 through condenser C_8 and resistance R_{12} .

Tube T_2 may comprise cathode T_{2c} , control grid T_{2g} , and anode T_{2a} . Cathode T_{2c} may be connected to ground through resistance R_{13} and control electrode T_{2g} to ground through resistance R_{12} . Anode T_{2a} may be connected directly to the $+B$ source.

A blocking oscillator is provided, comprising tube T_3 , which may have cathode T_{3c} , control electrode T_{3g} , and anode T_{3a} . The cathode may be connected to ground and the anode through the primary $10p$ of feedback transformer 10 , and through condenser C_{11} to cathode T_{2c} of tube T_2 .

The common point of winding $10p$ and condenser C_{11} may be connected to ground through resistance R_{14} . The secondary $10s$ of feedback transformer 10 may be connected at one end to ground and at the other through resistance R_{10} and condenser C_9 in parallel to control electrode T_{3g} of tube T_3 , and also through condenser C_{12} to the control electrode of tube T_4 .

This may be a tube of the thyratron type, having cathode T_{4c} , control electrode T_{4g} , shield electrode T_{4sg} (herein shown as connected directly to cathode T_{4c}), and anode T_{4a} , which may be connected through resistance R_{15} to the $+B$ supply and to one terminal of the artificial line AL , the other terminal of which may be the output terminal and may be connected to ground through resistance R_{11} . Cathode T_{4c} of tube T_4 may be connected to ground through resistance R_{15} shunted by condenser C_{10} and to the $+B$ supply through resistance R_{16} .

The operation of the circuit will now be described. Suppose that switch S_1 is closed on its front contact S_1f . This opens the clearing circuit which previously existed in series through the back contacts of switches S_1 to S_4 , and grounds the common point of resistance R_4 and condenser C_3 . Since condenser C_1 has previously been charged to the value of the $+B$ supply through the connection afforded by resistances R_1 , R_2 , R_3 , and R_4 , closure of switch S_1 applies a strong negative pulse to the control grid of thyratron T_1 . This pulse leaks to ground in a time interval determined by the constants of the circuit formed by resistance R_5 and condensers C_1 , as shown

in Fig. 2a, wherein the dotted line represents zero or ground voltage.

The thyratron T_1 has previously been ionized, and the constants of the circuit are so chosen that the plate current is limited to about 0.3 ma. The value of resistance R_8 may be of the order of 0.5 megohm. Resistance R_9 , which may be from 0.5 to 1 megohm, forms a bleeder network which keeps the plate voltage within a value such that the weakest negative pulse applied to the control electrode T_{1g} of tube T_1 is sufficient to deionize the tube.

When the negative pulse is applied to control electrode T_{1g} by closure of switch S_1 on front contact, tube T_1 will deionize for the period of time represented in Fig. 2a by the intersection of the pulse curve with the zero axis. When thyratron T_1 deionizes at the beginning of the negative pulse, its plate voltage rises and remains at its full positive value until the negative impulse on the grid has been dissipated, at which time the tube reionizes and the plate voltage drops due to the increased I. R. drop in resistance R_9 . The plate voltage, therefore, has a pulse form as shown in Fig. 3a, the length of which is equal to the time tube T_1 was deionized, and this depends on the time constant of the resistance R_5 and capacity C_1 associated with switch S_1 .

While switch S_1 has been closed, the clearing circuit through the back contacts has been open, and thus condenser C_2 is permitted to charge through resistor R_7 . When switch S_1 is released, it goes to back contact and the circuit is ready to start another operation. In this connection it may be pointed out that the thyratron T_1 is preferably a type which will ionize in less than a microsecond.

Should any of the other switches S_2 , S_3 , or S_4 have been closed instead of switch S_1 , the action would have been the same except that the resistances and capacities associated with these switches are so chosen as to give a longer pulse. This is shown in Figs. 2b, 2c, and 2d, corresponding to closure of switches S_2 , S_3 , and S_4 , each producing a pulse of longer duration than the previous one.

Closure of any one of the switches S_1 to S_4 against its back contact at the conclusion of its closure on front contact causes discharge of condenser C_2 and applies a strong negative pulse on the shield grid T_{1sg} , and this causes deionization of tube T_1 in the same manner as if the pulse had been applied to control electrode T_{1g} . The time constant of the circuit associated with condenser C_2 is such that tube T_1 remains deionized for a longer period than for closure of switches S_1 , S_2 , S_3 , or S_4 on front contact.

The pulse in the plate voltage is thus of progressively increasing length for closure of switches S_1 , S_2 , S_3 , and S_4 , and for the clearing pulse, as shown in Figs. 3a, 3b, 3c, 3d, and 3e. These pulses are applied to control electrode T_{2g} of tube T_2 through coupling condenser C_8 and are amplified by tube T_2 . The output of tube T_2 is taken from its cathode T_{2c} and applied to the plate of blocking oscillator T_3 . This connection provides a pulse which is still positive, but in a circuit of lower impedance than that of the plate of tube T_1 .

Transformer 10 associated with tube T_3 and the constants of condenser C_9 and resistance R_{10} are such that the blocking and unblocking cycle is controlled by the R. C. circuit, and this may be made to have a blocking frequency of 1,000 cycles per second. The plate voltage of tube T_3 is indi-

cated in Figs. 4a, 4b, 4c, 4d, and 4e, and the short vertical lines indicate blocking cycles.

It will be observed that for closure of switch S1, the oscillator goes through two blocking cycles; for switch S2, three blocking cycles; for switch S3, four blocking cycles; for switch S4, five blocking cycles; and for closure of any of the foregoing back to its original (and normal) position, seven blocking cycles. The output of this oscillator is inherently pulse shaped, as shown in Figs. 5a, 5b, 5c, 5d, and 5e, and these pulses may then be applied to control electrode T4g of thyratron T4.

This tube is biased so that it is normally deionized and will ionize with the application of the pulses from the blocking oscillator. In the plate circuit of thyratron T4 there may be provided an artificial line AL, which is discharged when the tube is ionized. The discharge time of the line may be in the order of microseconds, and its charging time less than the time between successive pulses of the blocking oscillator, so that the line is always ready to discharge. Since the design and construction of artificial lines is well known in the art and forms per se no part of this invention, the same is not described in detail.

Negative pulses are available across the load resistor R11 and have the form indicated in Figs. 7a to 7e, corresponding to closures of switches S1 to S4 on front contact and closures of all switches on back contact respectively. Should positive pulses as indicated in Figs. 6a to 6e be desired, resistor 15 may be split and one leg isolated from ground by condenser C10 and the positive pulses taken from the high side of the isolated resistor which matches the artificial line AL.

Thus, with the blocking oscillator operating at 1,000 cycle blocking rate, the final pulse output is pulses of microseconds' length, depending upon the constants of the artificial line, and with the repetition rate depending upon the blocking frequency of the blocking oscillator.

While I have shown and described certain preferred embodiments of my invention, it will be understood that modifications and changes may be made without departing from the spirit and scope thereon, as will be clear to those skilled in the art.

In this application I have explained the principles of my invention and the best mode in which I have contemplated applying those principles, so as to distinguish my invention from other inventions; and I have particularly pointed out and distinctly claimed the part, improvement, or combination which I claim as my invention or discovery.

I claim:

1. In a pulse modulator circuit, in combination, a blocking oscillator having its constants so chosen as to generate pulses at a periodic rate, means for applying triggering voltages of different time length to said oscillator to provide groups of pulses of different numbers of pulses, an artificial line, means for maintaining said line always in a condition ready for discharge a thyratron having its plate connected to said artificial line to provide a discharge circuit therefor at a rate determined by said blocking oscillator, and for a time duration determined by said artificial line and means for controlling ionization of said thyratron in accordance with the pulses delivered by said blocking oscillator.

2. In a pulse modulator circuit, in combination,

a thyratron having a pair of control electrodes, a cathode and an anode, a plurality of switches, each having front and back contact and being normally biased to back contact, said switches being interconnected to provide an operating signal when all switches are closed on back contact and being selectively closable on front contact to provide a different operating signal, a time delay circuit for each operating signal, said time delay circuits corresponding to operating signals for front contact closures being connected to one of said control electrodes and said cathode whenever the corresponding switch is closed on front contact, and the time delay circuit corresponding to the back contact closure being connected to said cathode and the other of said control electrodes when all of said switches are closed on back contact.

3. In a pulse modulator circuit, in combination, a thyratron having a cathode, an anode, and a plurality of control electrodes, said thyratron having its constants so chosen as to be normally ionized, a plurality of time delay circuits connected between said cathode and one of said control electrodes for impressing on said control electrode negative pulses of varying duration to cause deionization of said thyratron for the duration of said pulses, and an additional time delay circuit connected to said cathode and to the other of said control electrodes, said last mentioned circuit being inoperative when any other time delay circuit is connected to said thyratron.

4. In a pulse modulator circuit, in combination, a plurality of control switches, each switch having front and back contacts and being biased to back contact, said switches being interconnected so that when all are closed on back contact an operating circuit is established, an ionized thyratron, means for applying, to said ionized thyratron, deionizing impulses of different length characteristic of closure of each particular switch and of closure of all on back contact, to deionize said thyratron for different times corresponding to each impulse; means for deriving a pulse form potential difference from the output circuit of said thyratron, means for producing groups of periodic discharges of pulse form, and means for controlling the length of said groups of said periodic discharges of pulse form in accordance with the pulse form potential difference derived from the output of said thyratron, to control the number of periodic pulses in accordance with closure of each particular switch.

ROBERT W. CARLSON.
